BOND OR TIE FOR BUILT-UP CRANK
SHAFTS

Karl Erik Kylén, Göttenborg, Sweden, assignor
to Aktiebolaget Svenska Kullagerfabriken, Got-
tenborg, Sweden, a corporation of Sweden

Application December 14, 1932, Serial No. 647,163
In Sweden September 12, 1932

7 Claims. (Cl. 74—598)

The present invention relates to improvements in bonds or ties, for built-up structures especially crankshafts, of the kind in which a member is formed hollow at the bond and is expanded in another member by means of a plug or the like inserted in the hole or cavity of the first mentioned member.

It has been previously known to make built-up crankshafts in which the crank pins are made hollow and have a conical or tapering inner surface. The crank pin is then fixed to the web by means of a tapering plug, which is driven or pressed into the conical hole with such force that the crank pin is expanded in the web and held rigidly in position by the pressure between the members. Such method of building up crankshafts has the great disadvantage that it is impossible to definitely fix the amount of "grip" between the members, since the grip depends upon the extent to which the tapering plug is forced into the crank pin. After having had the crankshaft apart for repairs there is always a risk that the plug will not be pressed home sufficiently tight, and that the joint will loosen, thereby destroying the crankshaft. This risk is, of course, especially great when the repairs are made in a small machine shop by mechanics having insufficient experience with the type of crankshaft in question, or where proper machinery for the assembly of the crankshaft is not available.

The object of the present invention is to provide a device in which the grip can be previously fixed, and in which the grip will always be the same upon reassembling the crankshaft after re-pairs. For this purpose the plugs are made with a substantially cylindrical, instead of conical, outer surface and with outer dimensions somewhat larger than the hole in the member into which they are to be inserted. The difference in dimensions will depend upon the amount of grip required. The greater the difference in dimensions, the greater will be the grip, but the greater will also be the force required to press home the plug. For this reason it is desirable to make the grip conform to that which will be required by the conditions at hand.

The accompanying drawings illustrate a number of forms of plugs and methods for assembling and dismantling the bond according to the invention.

In which drawings:

Figure 1 shows a method of mounting a pair of plugs, one in each end of a crank pin having a through hole.

Figs. 2 to 9 each shows an end view and an

axial section of a form of plug according to the invention.

Figs. 10 to 12 show methods of assembling plugs in crankshafts in which the crank pin is made in one piece with one of the webs.

Fig. 13 shows a method of dismantling a plug by means of a tool such as is illustrated in Fig. 15.

Figs. 14 and 15 respectively show a side elevation and end view, of two tools for assembling and dismantling a crankshaft.

Figs. 16 and 17 show two methods of removing a plug.

Fig. 18 shows a crank shaft in which one plug is used in two joints.

Fig. 19 shows plugs consisting of two concentric annular members.

Fig. 20 shows the invention applied to fixing a gudgeon pin in a connecting rod, and

Fig. 21 a device for increasing the friction in the joint.

The webs 1 in Fig. 1 are provided with through holes in which the crank pin 2 is to be fixed. The crank pin has a through hole in which the plugs 3 and 4 are inserted. The plugs are formed as annular members and are preferably chamfered at their inner ends to facilitate their insertion in the crank pin. A threaded bolt 5 is inserted through the holes in the plugs, which are forced home by drawing the nut 6. Between the plugs and the head of the bolt and the nut respectively are inserted washers 8 and 9 having an outer diameter larger than the outer diameters of the plugs. These washers serve to prevent either or both of the plugs from being forced too far into the crank pin.

The plug illustrated in Fig. 2 has been given a special form calculated to facilitate its removal. The plug is removed with the aid of a tool of the kind shown in Fig. 14 and in the manner shown in Fig. 13.

In the inner wall of the plug are two slots 11, and on its inner end a cross slot 12, the width of the latter being about the same as the width of the former. The dismantling tool 13 is threaded at one end 14 and is provided at the other end with a head 65. The head is provided with projections 15 so that its form is nearly the same as that of the hole in the plug. To remove the plug the head of the tool is passed through the hole in the plug and the tool turned a quarter of a revolution so that the projections 15 engage with the slot 12 as shown in Fig. 13. This prevents the tool from turning relative to the plug, thereby enabling the plug to be withdrawn by turning the nut. An annular member 16 and a washer 17 are passed over the tool after which

the nut 18 is screwed on and drawn until the plug is removed.

Fig. 3 shows a plug which differs from the plug illustrated in Fig. 2 in that it has four slots 18 and two cross slots 19. The plug is removed by means of the tool 20 illustrated in Fig. 15. The head of the tool is provided with four projections 21. After the tool has been inserted in the plug, it is turned an eighth of a revolution, and the plug 10 can then be removed in the manner described in connection with Fig. 13.

Figs. 4 and 5 show two plugs of substantially the same shape and adapted for use in the respective ends of the same crank pin. The plugs 15 22 and 23 are provided with circular through holes 24 and 25 and with cross slots 26 and 27. The plug 22 is removed in the manner shown in Fig. 13 by means of a tool of the kind shown in Fig. 14. The diameter of the shaft of the tool 20 is such that it fits the hole 24, and the diameter of the head across the projections is greater than the diameter of the hole 24, but less than the diameter of the hole 25. The tool is passed through the hole 25 with the threaded end first so 25 that the projections engage with the slot 26. The plug 22 can then be removed in the manner described above. The other plug 23 can then be removed in a similar manner by means of a larger tool of the same form, which is inserted from the 30 opposite direction.

Figs. 6 and 7 show two forms of plugs adapted for use in pairs. The plug 28, as shown in Fig. 6, is solid while the plug 29 is provided with a cylindrical hole, as shown in Fig. 7. To dismantle 35 the shaft the plug 28 is first knocked or forced out by means of a mandrel inserted through the hole in the plug 29. The plug 29 can then be removed with the aid of a mandrel of larger diameter inserted from the opposite direction.

40 Fig. 8 shows a plug 30 having a threaded hole. The plug is removed in the manner shown in Figs. 16 and 17. As shown in Fig. 16, a threaded tool 31 is screwed into the plug, which is then removed with the aid of an annular member 16, 45 a washer 17, and a nut 18, in the manner described in connection with Fig. 13.

According to Fig. 17 the crank pin is made in one piece with one of the webs 33 and is partly hollowed out to receive a plug such as 30 for fixing the crank pin in the other web 34. The plug 50 is forced out in this instance by means of a threaded tool 35 pressing against the bottom 36 of the hollow in the crank pin.

The plugs illustrated in Figs. 2 to 8 are preferably hardened, but the form shown in Fig. 9 is most suitably made of unhardened material. The plug is shown provided with an axial slot or channel 64. When it is desired to remove the plug its center part is drilled, or turned out almost to the bottom of the channel. The remaining annular part of the plug will exert so little pressure against the inner wall of the crank pin that it can be easily removed.

Several methods of assembling crankshafts in 65 which the crank pin is made in one piece with one of the webs are shown in Figs. 10 to 12. According to Fig. 10 a threaded hole 38 is formed at the bottom of the hollow 37 of the crank pin into which a tool 39 can be screwed. The hollow 70 plug 40 and the stop washer 41 are passed over the tool after which the nut 42 is applied and drawn. When the plug has been forced in as far as the stop washer will allow the tool 39 is screwed out of the threaded hole and removed.

75 According to Fig. 11 both the crank pin 43 and

the web 44 are drilled through to allow a tool 46 provided with a head 45 to be passed through the hole. The plug can then be forced home in the manner described above.

In Fig. 12 the tool 47 is threaded to enable it to be screwed into a threaded hole in the web. The head of the tool 48 is made large enough to perform the duty of a stop washer.

Fig. 18 shows a device in which a single plug 49 serves to fix the crank pin 50 to both the webs 10 51 and 52. The pin should preferably not be expanded between the webs. The crank pin, or the plug, or both, are therefore formed so that there will be a clearance 53 between them along 15 this part of the crank pin.

Fig. 19 shows a device in which each plug consists of two concentric annular members. By this means it is possible to increase the pressure against the pin 54. When assembling the 20 crankshaft the larger member 55 is first pressed home in the pin 54 and expands the pin to fix it to the web. The smaller member 56 is then inserted in the larger one 55 which is expanded. This expansion is communicated to the pin 54, further increasing the friction between the pin 25 and the web.

Fig. 20 shows the invention applied to a gudgeon pin having its bearings in the piston bosses. The gudgeon pin 57 is fixed to the connecting rod 58 by means of a plug 59 which is 30 preferably made in one of the above mentioned forms to facilitate dismantling.

Fig. 21 shows an arrangement for increasing the friction and strength of a joint. The plugs 60 are provided with flanges 61, which are secured to 35 the webs in some suitable manner, for instance by means of rivets 62. If desired, the flange 64 of a crank shaft plug may be secured by providing it with a hole and allowing the crank pin to project through this hole as shown at the left hand 40 side in Fig. 21. By these means a part of the torque can be transmitted from the web to the shaft by means of the friction between the plug and the shaft. Similar flanges as 65 also on the left hand side of Fig. 21, may be provided on the 45 plugs 63 of the crank pin, if desired.

By a suitable choice of the diameters of the plug and the hole in the crank pin it is possible to adapt the grip according to the requirements. In cases where one of a pair of plugs is thicker 50 than the other, the thinner plug may be made slightly larger than the other so that the pressures exerted by both plugs will be substantially equal. In order to guard the pin from dangerous tension, and to increase the pressure between the 55 pin and the surrounding part, the outer diameter of the pin can be made slightly greater than the diameter of the hole into which it is to be inserted. In this manner it will be possible to obtain an initial pressure between the pin and 60 the surrounding part which will compress the end of the pin somewhat when it is driven, forced or shrunk in. When the plug is forced into place the pin is again expanded to its original diameter, thus sparing it from being subjected to considerable tension.

The invention is not confined to the forms illustrated, but can be applied to a number of places and in a number of ways falling under the claims. The plugs can either be driven in 70 by blows, or may be pressed in, for example by hydraulic means, or may be shrunk in place by heating the surrounding parts, or by cooling the plug in some suitable manner, for instance in liquid air.

Having thus described my invention I claim and desire to secure by Letters Patent:

1. A bond for a built-up crankshaft, one member having a bond receiving cavity and another member having a bond portion seated in such cavity, there being a plug receiving cavity in such bond portion formed with an uninterrupted cylindrical wall, and a plug having a cylindrical outer surface seated in the hollow cavity in the said bond portion expanding it into the bond receiving cavity in the first named member, the plug constituting the sole means for bonding the two members.
2. A bond for a built-up crankshaft, one member having a bond receiving cavity and another member having a bond portion seated in such cavity, there being a plug receiving cavity in such bond portion formed with an uninterrupted cylindrical wall, and a plug having a cylindrical outer surface seated in the hollow cavity in the said bond portion expanding it into the bond receiving cavity in the first named member, the plug constituting the sole means for bonding the two members, such plug being formed with a hole extending axially through it for facilitating its insertion and removal.
3. A bond for a built-up crankshaft, one member having a bond receiving cavity and another member having a bond portion seated in such cavity, there being a plug receiving cavity in such bond portion formed with an uninterrupted cylindrical wall, and a plug having a cylindrical outer surface seated in the hollow cavity in the said bond portion expanding it into the bond receiving cavity in the first named member, the plug constituting the sole means for bonding the two members, such plug being formed with a screw threaded hole extending axially through it for facilitating its insertion and removal.
4. A built-up crankshaft comprising a pair of members each formed with a bond receiving cavity, a hollow crank pin having its ends seated in such cavity, the internal walls of the end portions of the pin being formed with uninterrupted cylindrical surfaces, and plugs having cylindrical outer surfaces seated in the respective ends of the pin expanding them into the cavities in the first

named member, the plugs constituting the sole means for bonding the members.

5. A built-up crankshaft comprising a pair of members each formed with a bond receiving cavity, a hollow crank pin having its ends seated in such cavity, the internal walls of the end portions of the pin being formed with uninterrupted cylindrical surfaces, and plugs having cylindrical outer surfaces seated in the respective ends of the pin expanding them into the cavities in the first 10 named member, the plugs constituting the sole means for bonding the members, at least one of such plugs being formed with a hole extending axially through it, such hole having one or more maximum dimensions and one or more minimum 15 dimensions.

6. A built-up crankshaft comprising a pair of members each formed with a bond receiving cavity, a hollow crank pin having its ends seated in such cavity, the internal walls of the end portions of the pin being formed with uninterrupted cylindrical surfaces, and plugs having cylindrical outer surfaces seated in the respective ends of the pin expanding them into the cavities in the first 20 named member, the plugs constituting the sole 25 means for bonding the members, such plugs being formed with holes extending axially through them, the maximum cross sectional dimension of the hole in one of the plugs being greater than the minimum cross sectional dimension of the 30 hole in the other plug.

7. A built-up crankshaft comprising a pair of members each formed with a bond receiving cavity, a hollow crank pin having its ends seated in such cavity, the internal walls of the end portions of the pin being formed with uninterrupted cylindrical surfaces, and plugs having cylindrical outer surfaces seated in the respective ends of the pin expanding them into the cavities in the first named member, the plugs constituting the sole 35 means for bonding the members, at least one of such plugs being formed with a hole extending axially through it, the axially extending hole in the plug having one or more cross sectional maximum dimensions and one or more cross sectional 40 minimum dimensions.

KARL ERIK KYLÉN.
